UNITED STATES PATENT OFFICE.

GRENVILLE J. LYNN, OF LOS ANGELES, CALIFORNIA.

APPARATUS FOR PRIMING AND DECARBONIZING INTERNAL-COMBUSTION ENGINES.

1,115,846.

Specification of Letters Patent.

Patented Nov. 3, 1914.

Application filed December 22, 1913. Serial No. 808,094.

To all whom it may concern:

Be it known that I, GRENVILLE J. LYNN, a citizen of the United States, residing at Los Angeles, in the county of Los Angeles, 5 State of California, have invented new and useful Improvements in Apparatus for Priming and Decarbonizing Internal-Combustion Engines, of which the following is a specification.

10 This invention relates to an apparatus for priming and decarbonizing internal combustion engines.

It is the object of this invention to provide an apparatus whereby a measured quantity 15 of either a priming or decarbonizing fluid may be injected into the cylinders of gas engines at will for the purpose of starting or accelerating the engine and for removing accumulations of carbon from the engine cylinders and internal parts.

20 A further object is to provide an adjustable means in an apparatus of the above character whereby the quantity of the priming liquid and decarbonizer may be regulated to suit variable conditions so that the apparatus can be applied to gas engines of various types and sizes.

Another object is to provide a combined 25 priming and decarbonizing apparatus which is simple in construction and efficient and reliable in operation.

Other objects will appear hereinafter.

The invention primarily resides in a pair 30 of reservoirs for the reception of the priming and decarbonizing liquids, a pair of pumps mounted to operate simultaneously, means whereby the intake of both of the pumps can be connected to either of the reservoirs, and means whereby the discharge 35 openings of either of the pumps may be separately connected to either of the reservoirs or to the cylinders of an engine.

The invention consists of the parts and construction and combination of parts as 40 hereinafter more fully described and claimed, having reference to the accompanying drawings, in which;

Figure 1 is a view in front elevation of the 45 apparatus with portions broken away to show the plunger construction of the pumps. Fig. 2 is a plan view. Fig. 3 is a diagrammatic view illustrating the application of the invention and showing the control valves in section. Fig. 4 is an enlarged detail section of one of the control valves.

In the drawings, 5 and 6 indicate reservoirs of any suitable construction for the reception of the priming and decarbonizing fluids respectively, which reservoirs may be mounted at any convenient point and are 60 fitted with perforated caps 7 closing their intake openings. A pair of corresponding pumps 8 and 9 are mounted in parallel relation to each other adjacent to the reservoirs 5 and 6 which pumps are fitted with reciprocating pistons 10 and 11 adjustably mounted by means of nuts 12 on the threaded lower ends of piston rods 13 and 14, which piston rods are connected at their upper ends to a cross bar 15. A hand lever 65 16 pivoted at 17 is connected at 18 to the cross bar and is provided for the purpose of reciprocating the pistons 10 and 11 in the cylinders of the pumps 8 and 9 simultaneously in one operation.

The lower ends of the pump cylinders are formed with valved intake openings which connect with a single conduit 19 which leads to the port 20 in the casing of a three-way valve *a*; the inlet ports 21 and 22 of which 70 connect with conduits 23 and 24 which connect with the lower ends of the reservoirs 5 and 6. The three-way valve *a* is provided for the purpose of controlling communication between both of the pumps 8 and 9 and 75 either reservoir 5 and 6, according to whether it is desired to draw the priming fluid or the decarbonizing fluid into the pumps; the valve *a* being formed with the usual three-way passage 25, which on the turning of the 80 valve will form a communication between the ports 20 and 21 or between the ports 20 and 22.

The outlets 26 of the pumps 8 and 9 are formed near their lower ends and connect 85 with pipes 27 leading to ports 28 and 29 in the casings of three-way valves *b* and *c*, which valves correspond in construction with the valve *a* and are formed with three-way passages 30 and 31; the casing of the 90 valve *b* having ports 32 and 33 which connect with pipes 34 and 35 respectively; the pipe 34 leading to an engine cylinder 36 above the piston therein through a check valve 37 and the pipe 35 connecting with the 95 port 38 in a three-way valve *d*. The casing of valve *c* is provided with ports 39 and 40 which connect with pipes 41 and 42 respectively; the pipe 41 connecting with an engine cylinder 43 through a check valve 44 100 105 110

and the pipe 42 connecting with the pipe 35 leading to the port 38 in the valve *d*. The valve *d* is provided with a three-way passage 45 and with ports 46 and 47 in its casting which ports connect with pipes 48 and 49 leading to the upper ends of the reservoirs 5 and 6 respectively.

The length of the strokes of the pistons 10 and 11 are regulated by means of adjustable stops 50 adapted to engage the cross bar 15 on its up stroke to limit the movement of the latter, which stops comprise pins insertible in any one of a series of perforations 51 formed in a standard 52. Any other means for limiting the strokes of the pistons 10 and 11 may be provided as desired. This adjustment of the piston stroke is for the purpose of regulating the quantity of liquid drawn into and discharged from the pumps at one operation.

In the operation of the invention, when it is desired to force a measured quantity of the priming liquid into either the engine cylinder 36 or 43, the three-way valve *a* is turned to close the port 22 and connect the ports 20 and 21 through the passage 25, thereby forming a connection between the reservoir 5 and the intake openings of the pumps 8 and 9. The hand lever 16, being previously disposed in its lowermost position, on being raised to its uppermost position, which is regulated by the stop pin 50, acts through the cross bar 15 to move the pistons 10 and 11 upward in the pump casings, thereby drawing a charge of the priming liquid into the pump casing below the pistons from the reservoir 5; the liquid being trapped in the pump casings by means of foot valves therein.

If it is desired to introduce the liquid into the engine cylinder 36 the valve *b* is turned to register with ports 28 and 32 to form communication between the discharge opening 26 of the pump 8 and the engine cylinder 36. The valve *c* will then be turned to connect the ports 29 and 40 so as to open communication between the discharge opening 26 in the pump 9 and the reservoir 5 through the valve *d* which is positioned to connect the ports 38 and 47. The pistons 10 and 11 now being forced down by the operation of the lever 16 will operate to discharge the liquid beneath the piston 10 into the engine cylinder 36 through the check valve 37 and discharge the liquid beneath the piston 11 back into the reservoir 5.

If it is desired to introduce the priming liquid into the engine cylinder 43 before operating the pistons 10 and 11 on the down-stroke, the valve *c* is turned to connect the ports 29 and 39 to form communication between the discharge opening 26 in pump 9 and the engine cylinder 43, and the valve *b* is turned to connect ports 28 and 33 to form connection between the pump 8 and the

reservoir 5. To introduce the priming fluid into both the engine cylinders 36 and 43 the valves *b* and *c* are turned to open communication between the pump 8 and the engine cylinder 36 and between the pump 9 and the engine cylinder 43.

When it is desired to introduce the carbonizing fluid into either or both of the engine cylinders 36 and 43, the valve *a* is turned to close the port 21 and connect the ports 20 and 22 through the passage 25, and the valve *d* is turned to close the port 47 and connect the ports 38 and 46. The up-stroke of the pistons 10 and 11 will then operate to draw the decarbonizing fluid into the pumps 8 and 9, whereupon the valves *b* and *c* are adjusted as before described to direct the fluid into either one or both of the engine cylinders, or back to the reservoir 6.

From the foregoing it will be seen that the pumps 8 and 9 will operate to simultaneously draw the liquids from either reservoir 5 and 6 and will discharge the liquid into either or both engine cylinders or back into the reservoir when it is undesirable to deliver it to both engine cylinders. It may be advantageous at times to mix the liquids of the reservoirs 5 and 6 either in the pumps or by transferring the liquid from one reservoir to the other. This can be readily accomplished by positioning the valves *a* *b* *c* and *d* according to the end sought.

While I have shown the invention as applied to a two-cylinder engine and employing two reservoirs, and two pumps, it is obvious that the number may be increased to any desired extent, such for instance, where an apparatus is to be attached to a four-cylinder engine, a set of four pumps would be employed and connected to the reservoirs 5 and 6 and to the two additional engine cylinders in the manner shown and described in connection with two cylinders herein referred to.

What I claim is:

1. In an apparatus of the class described, a plurality of pumps, means for manually operating said pumps synchronously, and means whereby a single operation of the pumps will act to deliver one or the other of several liquids to one or more engine cylinders or back to the source of liquid supply.

2. An apparatus for introducing priming and decarbonizing liquids into gas engines, comprising a pair of reservoirs, a plurality of pumps, means for operating the pumps simultaneously, connections between the intake openings of the pumps and each of the reservoirs, a single valve for opening communication between either of the reservoirs and all the pumps, communications between the discharge openings of the pumps and the engine cylinders and with the reservoirs, and valve means for direct-

ing the liquids discharged from the pumps to either or all of the engine cylinders or to either of the reservoirs at will.

3. In an engine priming device, a series of pumps, means for manually operating said pumps in unison, a pair of reservoirs, conduits connecting the lower ends of said reservoirs and the intake ends of the pumps, a three-way valve in said conduit adapted to open communication between either of the reservoirs and the pumps adapted to open and close communication between either of the reservoirs and the pumps, means for adjusting the pump stroke 10 to regulate the quantity of liquid handled

thereby, connections leading from the discharge openings of the pumps to the engine cylinders and to the upper ends of the reservoirs, valve means for directing the discharge of the pumps to either or all of the 20 engine cylinders or to either of the reservoirs.

In witness that I claim the foregoing I have hereunto subscribed my name this 3rd day of December, 1913.

GRENVILLE J. LYNN.
